UNITED STATES PATENT OFFICE.

SAMUEL M. VAUCLAIN, OF PHILADELPHIA, PENNSYLVANIA, ASSIGNOR, BY MESNE ASSIGNMENTS, TO BALDWIN LOCOMOTIVE WORKS, OF PHILADELPHIA, PENNSYLVANIA, A CORPORATION OF PENNSYLVANIA.

DEFLECTOR FOR SMOKE-BOX SUPERHEATERS OR FEED-WATER HEATERS.

978,795.

Specification of Letters Patent. Patented Dec. 13, 1910.

Application filed January 22, 1908. Serial No. 412,132.

To all whom it may concern:

Be it known that I, SAMUEL M. VAUCLAIN, a citizen of the United States, residing in Philadelphia, Pennsylvania, have invented 5 certain Improvements in Deflectors for Smoke-Box Superheaters or Feed-Water Heaters, of which the following is a specification.

My invention relates to certain improvements in superheaters or feed water heaters which are situated in the smoke box of a locomotive.

The object of my invention is to provide 10 a deflector which will cause the products of combustion passing from the tubes of the boiler to pass through the superheater tubes before passing to the stack. This object I attain in the following manner, reference being had to the accompanying drawings, in which:

Figure 1, is a longitudinal sectional view 15 on the line 1—1 Fig. 2, illustrating my invention; Fig. 2, is a sectional plan view on the line 2—2 Fig. 1; Fig. 3, is a transverse 20 sectional diagram view on the line 3—3, Fig. 1, drawn to a reduced scale, and Fig. 4, is a transverse sectional view in diagram illustrating my invention as applied to a smoke box feed water heater.

A is the boiler having tube sheet a and tubes a' .

A' is the casing of the smoke box.

B is the stack.

C is the nozzle and B' is the hood mounted 30 on the nozzle directly under the stack.

D, D' are the superheaters, one placed on each side of the smoke box and conforming to the shape of the casing of the smoke box, and, in the present instance, each superheater section has an upper or saturated 40 steam header d , a lower or superheated steam header d' and tubes d'' . The upper headers d are connected to the steam supply pipe c leading from the boiler, while the lower headers are connected to the steam 45 passages in the cylinders of the locomotive. This particular type of superheater is fully described and claimed in an application for patent filed by me on the seventh day of 50 December, 1905, Serial No. 290,796.

In order to direct the products of combustion from the tubes of the boiler through the spaces between the superheating tubes, I form a discharge casing or deflector con-

sisting of two vertically arranged plates 55 E—E, one mounted on each side of the nozzle C and extending from the base of the smoke box to the roof in the present instance as clearly shown in Fig. 3. Each deflector is shaped as clearly shown in said figure, 60 the space between the deflectors being narrow at the top and bottom and enlarged at the center allowing sufficient space for the hood B' and also causing the products of combustion to pass in close proximity to 65 and through the spaces between the tubes. The two plates E—E of the deflector I preferably extend parallel in front of the nozzle but they are inclined toward each other from the nozzle to the forward tube sheet a , 70 as clearly shown in plan view, Fig. 2, and the inner ends of the plates are secured together in any suitable manner. It will be noticed on referring to Figs. 1 and 2, that the plates extend to a point near the front 75 wall A^2 of the smoke box and I perforate the side plates E at e — e forming lateral draft openings which allow the products of combustion to pass through the perforations, as well as around the plates to the stack. 80 These perforated or grated sections e may be made of a separate plate set into the deflectors E and the perforations may be in the form of slots, as shown, or the perforations may be circular or the sections e formed 85 of fine gauze; the object being to make the perforations of such a size that coarse sparks and cinders will not pass through the perforations, but will be deflected and dropped to the bottom of the smoke box. In order 90 to allow room for the steam supply pipes to the superheaters the vertical plates E—E are cut away as shown in Fig. 1, and a horizontal plate e' extends across the smoke box from one side to the other as clearly shown 95 in Figs. 1 and 3, so as to deflect the products of combustion; the tubes of the boiler not extending above this plate.

I mount a screen F in the space between the plates E—E extending from the nozzle 100 C to the roof of the smoke box and this screen is preferably arranged at an incline as shown clearly in Fig. 1 and detachably secured in place so that it can be removed when it is desired to gain access to the hood. 105 This screen prevents the escape of cinders of any size to the stack the cinders dropping down onto the floor of the smoke box.

The products of combustion will be deflected by the vertical plates E—E and will pass through the spaces between the tubes of the superheater and will pass around the forward ends of the plates and a given portion will pass through the perforated sections e of the plates. Thus the superheating tubes will be properly heated and the waste products of combustion will readily pass to the stack.

In Fig. 4, I have illustrated my invention as applied to a smoke box feed water heater, the feed water heater being made in sections D'—D' somewhat similar to sections D of the superheater. Each section has an upper head d^2 and a lower head d^4 , the lower heads being connected together by pipes i and the upper heads being attached to pipes I'—I', one connected to the water supply and the other to the boiler. The deflecting plates in this construction are similar in all respects to the plates in the superheater and deflect the products of combustion in the same manner causing the products of combustion to pass through the spaces between the tubes of the feed water heater.

I claim:

1. The combination with a boiler of a smoke box, a series of tubes within the smoke box and at each side of the center thereof, and vertically arranged deflecting plates within the smoke box placed to cause the products of combustion to pass through the spaces between the tubes, the portions of the said plates distant from the boiler being perforated.

2. The combination of a locomotive boiler having a smoke box, a nozzle extending into the smoke box, tubes mounted at the sides of the smoke box, vertically arranged deflecting plates mounted also in the smoke box at each side of the nozzle, the ends of said plates adjacent to the boiler being inclined toward each other, and the other ends of the plates being perforated, with an inclined screen arranged between the plates.

3. The combination with a tubular steam boiler, of a set of steam headers in the upper portion of the smoke box communicating with the main steam supply pipe of the boiler, a second set of steam headers in the lower portion of the smoke box communicating with branch steam pipes leading to en-

gine cylinders, sets of superheater pipes located at opposite sides of the smoke box and connecting the headers of the two sets, deflecting means extending in the smoke box in front of the tube sheet, with a discharge casing extending longitudinally from the deflecting means to the smoke box front and vertically from the exhaust pipe to the lower opening of the stack, there being lateral draft openings in the discharge casing, and a screen covering said draft openings.

4. The combination with a tubular steam boiler, of a T-head, saturated steam headers in the smoke box on opposite sides of the T-head and communicating therewith, superheated steam headers secured to opposite sides of the smoke box near the lower portion thereof, sets of superheater pipes located on opposite sides of the smoke box and connecting the saturated and superheated steam headers on each side thereof, deflecting means in the smoke box in front of the tube sheet, a discharge casing extending longitudinally from the deflecting means to the smoke box front and vertically from the exhaust pipe to the lower opening of the stack, there being lateral draft openings in the discharge casing, and a screen covering said openings.

5. In a locomotive boiler having a smoke-box which receives heated gases at one end, the combination of means in said smoke-box forming a central discharge chamber closed from communication with the rest of the smoke-box except at its end remote from the point of ingress of the gases thereinto and discharging at its other end through an outlet in the side of the smoke-box, the wall of said chamber at its end remote from the point of ingress of the gases into the smoke-box being foraminous to allow ingress of said gases into said chamber, and superheating means in said smoke-box in the path of the gases as they pass from their point of ingress thereinto to their point of ingress into the discharge chamber.

In testimony whereof, I have signed my name to this specification, in the presence of two subscribing witnesses.

SAMUEL M. VAUCLAIN.
